SELF-CLEANING PUSH BRUSH

Dorsey T. Price, Knoxville, Iowa

Application January 25, 1949, Serial No. 72,593

2 Claims. (Cl. 15—160)

1

My present invention relates to the general class of brushes and brooms, and more specifically to an improved self cleaning push brush or broom of the long handle type that is adapted for sweeping or brushing domestic floors, and especially designed for use in brushing or sweeping floors of public buildings or other places having large floor areas. The primary purpose of the invention is the provision of an automatically operating implement that is durable and reliable for efficiency in thoroughly cleaning a floor by eliminating the usual starting and stopping dirt-spots left at the ends of the working strokes. For this purpose the hand operated implement includes a brush mounted on the handle with the brush initially and resiliently retained in inoperative position alined with or at an obtuse angle to the handle, and by pressure of the working stroke of the handle the floor-supported brush is automatically tilted or swung backwardly to a working position at a more acute angle to the axial line of the handle, to push the dirt forwardly. At the end of the sweeping stroke the resiliently and pressure-retained brush is automatically snapped forwardly to initial position thereby flipping and advancing the sweepings over the unswept portion of a floor for another sweeping stroke of the brush.

The implement includes a minimum number of parts that may with facility be manufactured at low cost of production, and the parts may be assembled with convenience to assure a smooth working and easily operated brush that is simple in construction and operation. The invention consists in certain novel features of construction and combinations and arrangements of parts as will hereinafter be described and more particularly set forth in the appended claims.

In the accompanying drawings I have illustrated a complete example of a physical embodiment of my invention in which the parts are combined and arranged in accord with one mode I have thus far devised for the practical application of the principles of the invention.

Figure 1 is a view in side elevation of the brush in working position, and showing by dotted lines the brush in snapped or ejecting position.

Figure 2 is a rear view of the brush with the handle broken away for convenience of illustration.

Figure 3 is a front view similar to Fig. 2.

Figure 4 is a view showing the brush at the end of its snapped or ejecting position.

Figure 5 is a top plan view of the head of the brush; and

Figure 6 is an enlarged perspective view of a spring-supporting collar detached from the brush.

The brush B and handle H are fashioned in conventional size and shape, and the brush-head 1, which may be of wood or other suitable material is equipped with a metallic rectangular base plate 2, preferably rounded to conform to the crown of the head, is rigidly attached to the head as by screws 3.

The base plate is provided with two aligned and spaced attaching ears or perforated lugs 4, 4, disposed toward the front of the brush, and with a parallel pair of perforated ears or bearing bosses 5, 5 disposed toward the back of the head of the brush. These pairs of bearing elements are spaced parallel with the longitudinal axis of the head, and the members of each pair are located laterally of the handle, or its longitudinal axis.

The handle H is coupled to the front bearings 4, 4 by means of a socket-sleeve 6 of metal or other suitable metal, fitted on its lower or front end, and the sleeve, which is fixed by a screw 7 to the handle, is provided with a forwardly projecting flange 8 that terminates in a perforated bearing boss or ear 9. The bearing boss 9 is fitted between the two ears 4, 4, and a pivot bolt 10 passed through the ears and the boss, retains these parts in pivotal relation with the brush in initial non-working position as shown by dotted lines in Fig. 1.

In this non-working, or rather non-brushing position of the brush, the implement may be employed for sweeping strokes as with the manipulation of a broom; but for brushing strokes across a floor, the brush is held at a more acute angle to the axial line of the handle, by forward pressure on the handle on the working stroke of the brush, as the latter is pushed along the floor.

For coaction with this pushing or pressure action on the brushing stroke, resilient means are provided to impart a snapping action to the brush, at the end of the stroke, for ejecting dust and dirt therefrom, and for pushing the collected sweepings forwardly over the unswept or unbrushed floor.

The resiliently operated device is mounted by means of a split resilient clamping collar or band 11 that is clamped on the handle above the sleeve 6 by means of outstanding flanges 12 that are perforated to receive the clamping bolt 13 that is secured by nut 14. The collar is fashioned with a rearwardly extended and perforated flange 15 to receive an eye-bolt 16 having an upper head 17 and which is arranged at the rear of the

handle with its eye fitted between the two ears 5, 5, and coupled thereto by a pivot bolt 18.

A compression spring 19, coiled about the bolt, is interposed between the flange 15 and a washer 20 mounted on the eyebolt just above its eye.

By this arrangement of parts the handle and the brush are pivoted at 10 in front of the longitudinal axial line of the brush head, and at 18, at the rear of this axial line, and the pivot 18 has a resilient anchorage on the handle. Thus, pressure against the front pivot, against the floor supported brush tends to swing the brush under and backward against tension of the spring, and when, at the end of a brushing stroke, this pressure is released, the compressed spring expands and swings the brush, with a snapping forwardly and upwardly to dotted position of Fig. 1, for forwardly ejecting the collected sweepings or brushings.

When pressure through the handle is released at the end of each brushing stroke, pressure is again applied to the handle for initiating the next brushing stroke.

The same action of the brush is accomplished and the same results are attained when the implement is used in manner similar to operating a broom; and as the implement is oscillated on its forward swing the floor supported brush is swung on its pivot, and then at the end of the sweeping stroke, by resilient action of the brushing the sweepings are ejected forwardly.

Having thus fully described my invention, what I claim as new and desire to secure by Letters Patent is:

1. In a self cleaning pushing brush, the combination with a handle and a brush head, of a socket-sleeve rigid with the handle and means for pivotally connecting the sleeve with the front portion of the brush head, a clamp collar rigid with the handle and an eyebolt slidably attached

5 to the collar, said eyebolt having a pivotal connection to the rear portion of the brush head, and a compression spring mounted on the eyebolt between the collar and the pivotal connection.

2. In a self cleaning pushing brush, the combination with a brush head saving an attaching plate, said plate having a pair of spaced bearings in front of its longitudinal axial line and a complementary pair of spaced bearings at the rear of said line in opposed relation to the said first bearings, of a handle, a sleeve rigid with the handle, an integral bearing on the sleeve below the lower end of the handle fitted between the front bearings and a pivotal bolt uniting these bearings, a collar clamped on the handle above the sleeve and a perforated flange integral with the collar, a headed eyebolt mounted in the flange, a pivotal bolt uniting the eyebolt with the complementary spaced rear bearings, a washer on eyebolt the adjacent the pivoted bolt, and a compression spring coiled about the eyebolt and interposed between said washer and the flange of the collar.
